UNITED STATES PATENT OFFICE.

MARK L. J. KEHOE, OF CHICAGO, ILLINOIS.

DIRT COLLECTOR FOR BOWLING-ALLEY PITS.

Application filed March 31, 1927. Serial No. 179,833.

My invention pertains to a dirt collector for bowling alley pits, and more particularly to a device for gathering dirt and dust from the pit and from the mat therein.

5 During bowling as the pins are knocked down they stir up dust and dirt, and in many bowling alleys a mat or meshed permeable member is placed in the pit, being elastic and sound deadening, for the pins to drop on; and 10 considerable dust and dirt is collected by the mat and is forced, by the dropping pins and gravity, through the mat onto the floor beneath it.

The main object of this invention is to provide a device and means therewith for collecting the dust and dirt occurring in the bowling alley pit, and moreover to provide means for collecting and withdrawing the dust and dirt which is usually gathered by 20 the mat, where a mat is used, and dropped by it on the floor beneath the mat. Another object is to construct the device with a perforated upper member adapted to support the falling pins and arranged to permit the passage of dust and dirt therethrough, and to gather said dust and dirt in containing means therebeneath. A further object is to provide the device with means for forcibly withdrawing and conveying the dust and dirt from the 25 container and from the upper pin-supporting member, and even from the mat positioned on said member.

These objects and other objects and advantageous ends are attained with my invention, as will become apparent from the following description, taken in connection with the accompanying drawings, in which,

35 Fig. 1 is a plan view, showing the preferred form of my invention mounted in position in a bowling alley;

40 Fig. 2 is an enlarged vertical sectional view, taken along line 2—2 on Fig. 1;

Fig. 3 is a plan view of the upper perforated member;

45 Fig. 4 is a vertical sectional view, taken along line 4—4 on Fig. 2;

Fig. 5 is an enlarged vertical sectional view, taken along line 5—5 on Fig. 4; and

50 Fig. 6 is a vertical sectional view, taken along line 6—6 on Fig. 5.

In the drawings I have illustrated my invention in its preferred form of construction, which comprises the device or means mount-

able in the pit 11 of a bowling alley 12, and is here shown as interposed in or taking the 55 place of the pit floor, in position for supporting the pins 13 as they are knocked from the alley into the pit. These alleys are generally provided with sound-deadening or cushioning means, as a rear cushioning member 14 and a floor mat or member 15 on which the pins drop and which is usually braided or permeable, thus being resilient and also apt 60 to take up dust and dirt and let same pass through it to the floor or supporting means 65 beneath.

The present form of my invention comprises an upper member or means 16 arranged for mounting in the pit floor, and is preferably substituted for part of the pit floor, in 70 position to receive and support the pins 13 as they are knocked over. This means 16 is also arranged in a shape and size and sufficiently rigid and strong to receive and carry the mat 15 thereon, when the mat is used, and 75 contains perforations or spaces for the passage therethrough of dust and dirt from the pit, and from the mat supported thereon. Said member 16 may be economically constructed from bars 17 which are spaced by spacers 18, 80 to provide perforations or spaces 19 for the passage of dirt and dust, and said bars and spacers being fastened together by rods 20. This member is adapted to serve the purpose of and to function as the usual pit floor, and 85 may be supported on the usual supporting means 11' of the pit, as best indicated in Fig. 4.

I further provide my device with a container member or means 21 for collecting the dirt and dust, and this is placed beneath member 16, and preferably has a tapering bottom or depending lower portion which ends in or is provided with a tapered discharge member or funnel 22. A discharge pipe or conduit 23 is attached to this funnel to 90 convey the dirt and dust from the container. A slide valve 24 is mounted at the bottom of said lower portion, and preferably at the top of funnel 22, as by means of brackets 25 and 26, or in any suitable manner, to close or 95 shut-off the bottom of the container from the conduit when desired.

In addition to the above described construction I furthermore provide my device, when preferred or so requested, with mechanism or means for forcibly withdrawing the 100 105

dirt and dust from the container 21 and from the perforated member 16 above the same and thereby from the pit, and also from the mat on member 16 when the mat is used. 5 This means is preferably provided in the form of a suction pump 27 which is actuated by a motor or power member 28, and has an outlet or discharge member 29 thereon for discharging the dirt and dust therefrom into 10 any suitable receptacle for carrying the same away. The one forcing means or pump is sufficient for a series or plurality of alleys equipped with my devices, and the containers 21 through their funnels 22 and conduits 15 23 are then connected in series to the main conduit or conveying means 30 and thereby to the pump, as indicated in Fig. 1; or the pump may be connected with conduit 23 to the funnel 22 of the container 21 when one 20 device is employed; and the pump and conveying means are furthermore arranged and installed to suit the particular occasion.

It is apparent from the above disclosure that my device is very useful and efficient in 25 gathering and conveying the dust and dirt from the pit of the bowling alley, and with the suction means in action will even withdraw the dust and dirt from the mat as well as from the floor or the supporting means 30 beneath the mat; and furthermore that when the suction means or force means is not operative, or no suction means is employed, then the shut-off valve 24 can be closed and the dirt and dust allowed to collect in the container, and thereafter shoveled or removed 35 in any convenient manner therefrom after lifting up means 16, when the alley is idle.

The installation and continuous use of my device has proven it to be highly valuable and 40 efficient in removing dirt and dust from the bowling alley pit and from the mat therein.

What I claim as my invention and desire to secure by Letters Patent is:

1. A device for a bowling alley pit, comprising means arranged for mounting in the 45 pit in place of a fixed part thereof and to permit the passage of dirt therethrough, and a receptacle on said means for receiving the dirt therefrom. 50 2. A device for a bowling alley pit, comprising means arranged for mounting in the pit to replace a part thereof and for passage of dirt therethrough, and dirt collecting means therebeneath provided with valve controlled discharge means at the lower end.

3. A device for a bowling alley pit, comprising means arranged for mounting in the pit to replace a part thereof and for passage of dirt therethrough, container means mounted under it and below the floor for collecting dirt therefrom, and means for forcibly drawing and conveying the dirt from said container means.

4. A device for a bowling alley pit, comprising means mountable in the pit in place

of the pit floor and of sufficient size and strength to support the pins when knocked over and being provided with passages for dirt, and means thereunder with a tapering bottom for collecting the dirt. 70

5. A device for a bowling alley pit, comprising a level member mountable in the pit in place of a part of the pit floor, and containing spaced bars adapted to pass dirt therethrough, and container means mounted under the bottom of said member for collecting the dirt. 75

6. A device for a bowling alley pit, comprising means having elements spaced for the passage of dirt and arranged for installing 80 in the pit floor and substituted for a part of said floor, container means mounted therebeneath, and a discharge conduit at the lower end of said container means and having a shut-off valve at the bottom of said means. 85

7. A bowling alley having a pit, a member with openings therein positioned in the floor of said pit and adapted to support the falling pins, a receptacle mounted under the bottom of said member for collecting dirt, means for forcibly drawing and conveying the dirt from said collecting means, and means for closing off the collecting means from the conveying and drawings means, to permit manual removal of the dirt from said collecting 95 means. 90

8. A bowling alley having a pit and a mat therefor, a member with dirt passages therein installed in place of the floor of said pit to support the mat, a receptacle mounted under the bottom of said member for collecting dirt through said passages, a discharge conduit leading from the lower end of said container, a shut-off valve at the connection of said container and conduit, and means for forcibly 100 drawing the dirt from said conduit and container and even from said mat, and while the 105 bowling alley is in use.

9. A bowling alley having a pit and cushioning means therefor, a device for removing 110 dust and dirt from said cushioning means and pit, said device comprising means substituted for the pit floor and on which said cushioning means is mounted and supported and which is arranged for dust and dirt to 115 pass therethrough and drop beneath the floor.

10. A bowling alley comprising a pit which has the larger part of the customary floor omitted, and which has a dirt collecting device installed therein including a perforated 120 member mounted in place of the omitted part of said pit floor, and a receptacle mounted on the bottom of said perforated member, below the floor, for collecting a considerable amount of dirt dropping through said member and permit an extended continuous use of said bowling alley. 125

11. A bowling alley having a pit with the larger part of the pit floor omitted, said pit having a dirt collecting device installed there- 130

in and comprising a perforated member mounted in place of said omitted part of the pit floor, a receptacle mounted under said perforated member, and arranged for collecting a considerable amount of dirt dropping through said member and below the floor, and valve means on said receptacle to allow

the convenient removal of the dirt therefrom without interrupting the continuous operation of said bowling alley.

In testimony whereof I have signed my name to this specification.

MARK L. J. KEHOE.
